224,850

COMBINED TENT AND FLY COVER THEREFOR

Fred W. Enzel, St. Louis, Mo., and Edmund P. Hillary,
Auckland, New Zealand, assignors to Kellwood Com-
pany, St. Louis, Mo.

Filed June 17, 1971, Ser. No. 154,266

Term of patent 14 years

Int. Cl. D3—03

U.S. Cl. D88—3

FIG.1

FIG.2

FIG. 5

FIG. 3

FIG. 4

FIG. 1 is a perspective of a combined tent and fly cover therefor, showing our new design;

FIG. 2 is a front elevational view thereof;

FIG. 3 is a top plan view thereof;

FIG. 4 is a right side elevational view thereof, the left side being a mirror image thereof;

FIG. 5 is a rear elevational view thereof.

We claim:

The ornamental design for a combined tent and fly cover therefor, substantially as shown and described.
